UNITED STATES PATENT OFFICE.

DANIEL J. HARDING, OF LOUISVILLE, KENTUCKY, ASSIGNOR OF TWO-THIRDS TO PAUL CAIN AND ROY McDONALD, BOTH OF SAME PLACE.

STAMP-CANCELER.

SPECIFICATION forming part of Letters Patent No. 355,647, dated January 4, 1887.

Application filed April 30, 1886. Serial No. 200,658. (Model.)

To all whom it may concern:

Be it known that I, DANIEL J. HARDING, a citizen of the United States, residing at Louisville, in the county of Jefferson and State 5 of Kentucky, have invented certain new and useful Improvements in Stamp-Cancelers; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

25 Figure 1 of the drawings is a representation of this invention, and is a side view. Fig. 2 is a bottom view. Fig. 3 is a vertical section through the stamp-canceler. Figs. 4, 5, and 6 are details.

20 This invention relates to instruments for canceling stamps, checks, &c.; and it consists in the construction and novel arrangement of parts, as described, and pointed out in the claims.

25 In the accompanying drawings, the letter A designates the metallic body of the instrument, which may be provided with a metallic or wooden handle, B, which is usually attached to said body by means of its threaded extremity C, the latter engaging the threaded 30 bearing D in the body of the instrument. Usually I provide on one side of the body an ordinary dating-stamp, E, which is set upon a spring or springs and works upon a guide or guides.

35 As usually constructed, the body A consists of a cap-plate, G, and the boxing F and H, respectively, for the dating-stamp and for the canceler; or the body may be single, being provided only with the boxing H for the canceler. The boxing H is preferably cylindrical, and is formed with a central bore, I, in opposite sides of which are formed the oblique cam-grooves a a, which have an angular deviation 40 from the axial plane of about fifteen or twenty degrees, the object being to give a positive and quick action to the cutter K, whose stem P is provided with the studs c c on opposite sides, engaging said cam-grooves. Above the 45 central bore, I, in the boxing is the interspace i, which gives play to the cutter-stem and

guide-rods when the impact is made. Said boxing H is also formed with guide-apertures d d, parallel with the central bore and adapted to receive the guide-rods L of the bearing-head N. These guide-apertures are enlarged in their lower portions to receive the springs e, which engage the bearing-head and serve to bear it outward when not pressed down upon the stamp or paper. In the lower face of the 55 bearing-head is usually formed an annular groove or seat, f, for the annular pad g, of cork or other proper material. The bearing-head is, as shown, usually made of considerably greater diameter than the cutter, which works in the 60 central portion thereof, in order to assist in securing the true action of the latter, and to provide a guard to prevent the cutter from being forced too deeply into the envelope or other paper upon which the instrument is acting. To insure greater security in this particular the head N is provided with an outer circular guard, h, which is formed with oblique 65 slots k through which are passed the screws l, which engage threaded perforations of the 70 head. When these screws are loosened, the annular guard can be turned to adjust its heights relative to that of the cutter, so that the latter can be given just as much action as may be required. In this manner the head 75 may be adjusted to permit the cutter to act on the stamp of an envelope without cutting the material of said envelope under the stamp.

The central bearing, l, of the head N is usually cup-shaped or formed with a conical 80 bottom shoulder to provide a seat for the under portion of the cutter-head m, which is also usually conical in form, the object being to provide a bearing against which the cutter can easily and readily revolve when the impact is 85 made. As usually constructed, this bearing l is made in the form of a bushing let into the central opening of the head N.

The cutter K consists of the stem portion P and the head m. The stem portion is provided with the studs or projections c c on opposite sides, to engage the cam-grooves of the boxing H. It is also formed with a stop, o, at its inner end, to engage the inner end of the central bearing of the boxing, to prevent the 90 cutter from moving outward beyond a certain point. Usually this stop is made in the form 100

of a large-headed screw, which is secured in a central threaded perforation of the stem, as shown. The stem is also provided with transverse pin or stop *s*, which serves a similar 5 purpose with reference to the bearing-head *N*, preventing the cutter from projecting beyond the face of the latter beyond a certain point. It will be observed that in this construction 10 the instrument is adapted to be readily and easily taken to pieces for repair or other purpose.

The head of the cutter is usually somewhat larger in diameter than the stem, as hereinbefore indicated. Its face, which is set a little 15 outward or above the face of the head *N*, is formed with radial cutting edges, indicated at *v v*, made by removing V-shaped portions of the face of the cutter, as shown. The cutting edges are usually in the same plane, 20 and are rectilinear or so related to each other that their action will be uniform, the cuts made by them being of the same depth throughout.

The action of the cutter is rotary. In the 25 normal position the bearing-head *N* is held outward or away from the boxing by the spring action. When, however, the impact is made by a quick smart blow, the instrument being struck downward upon the stamped envelope or other matter, the boxing is forced 30

downward toward the bearing-head, and, moving along the stem of the cutter, acts upon the latter by the engagement of its cam-grooves to forcibly rotate the cutter when in intimate or forcible contact with the stamp, cutting the 35 latter to such depths as may be permitted by the adjustment.

Having described this invention, what I claim, and desire to secure by Letters Patent, is—

1. In a stamp-canceler, the combination, with the boxing having the oblique cam-grooves and guide-apertures, of the independent bearing-head, its guide-rods, and springs surrounding said rods, the cutter having stem 45 projection *C* engaging said cam-grooves and the stops, respectively, for the box-bearing and the head-bearing, substantially as specified.

2. In a stamp-canceler, the combination, with the bearing-head carrying a rotary cutter 50 centrally located, of the adjustable annular guard having oblique slots and the screws whereby said annular guard is secured to the bearing-head, substantially as specified.

In testimony whereof I affix my signature in presence of two witnesses.

DANL. J. HARDING.
